UNITED STATES PATENT OFFICE.

JOHN A. CRIMP, OF ELLENSBURG, WASHINGTON.

COIN-CONTROLLED MECHANISM.

1,217,716.

Specification of Letters Patent. Patented Feb. 27, 1917.

Application filed August 27, 1915. Serial No. 47,640.

To all whom it may concern:

Be it known that I, JOHN A. CRIMP, a citizen of the United States, residing at Ellensburg, in the county of Kittitas and State of Washington, have invented new and useful improvements in Coin-Controlled Mechanism, of which the following is a specification.

The invention relates to a vending machine, and more particularly to the class of coin controlled apparatus for attachment to liquid dispensing machines.

The primary object of the invention is the provision of an apparatus of this character wherein a predetermined quantity of liquid, such as gasolene, will be delivered from the machine upon the deposit of a single coin or a plurality of coins of a fixed valuation, thereby assuring the automatic delivery of the quantity of gasolene at the market price thereof to each and all of the users of the apparatus.

Another object of the invention is the provision of an apparatus of this character wherein the predetermined quantity of liquid can be delivered therefrom by the deposit of a single coin of twenty-five cents denomination, or a single coin of fifty cents denomination, or two coins of twenty-five cents and fifty cents denomination, thus assuring the automatic vending of the gasolene in determined quantities.

A further object of the invention is the provision of an apparatus of this character wherein the quantity of liquid to be delivered to the consumer upon the deposit of a coin therein can be regulated accordingly with respect to the variance in the market price of the liquid.

A still further object of the invention is the provision of an apparatus of this character wherein spurious coins deposited in the apparatus will not effect the successful operation of the apparatus for the dispensing of the predetermined quantities of liquid from the machine, and also such coins will be ejected from the apparatus and returned to the depositor.

A still further object of the invention is the provision of an apparatus of this character wherein the construction thereof is novel in form for the successful dispensing of predetermined quantities of liquid from the machine, and will obviate any possibility of the operation of the machine by

fraudulent deposits or improper manipulation thereof by unscrupulous persons.

A still further object of the invention is the provision of an apparatus of this character which is simple in construction, thoroughly reliable and efficient in operation, strong, durable, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings:—

Figure 1 is a vertical longitudinal sectional view through the casing showing the vending mechanism in side elevation.

Fig. 2 is a transverse horizontal sectional view.

Fig. 3 is a view similar to Fig. 1, showing the parts in shifted position.

Fig. 4 is a sectional view on the line 4—4 of Fig. 1.

Fig. 5 is a sectional view on the line 5—5 of Fig. 1.

Fig. 6 is a fragmentary top plan view of one of the slide bars.

Fig. 7 is a side elevation thereof.

Fig. 8 is a sectional view on the line 8—8 of Fig. 6.

Fig. 9 is a sectional view on the line 9—9 of Fig. 6.

Fig. 10 is a vertical sectional view through the coin receiving box.

Fig. 11 is a sectional view on the line 11—11 of Fig. 10.

Fig. 12 is a vertical sectional view taken through the main shaft, showing the escapement mechanism in side elevation.

Fig. 13 is a view similar to Fig. 12, showing the parts shifted.

Fig. 14 is a side elevation of the clutch controlling levers.

Fig. 15 is a fragmentary top plan view thereof.

Fig. 16 is a sectional view on the line 16—16 of Fig. 15.

Fig. 17 is a vertical longitudinal sectional view through the throw link controlling the clutch.

Fig. 18 is a plan view of the escapement slide.

Fig. 19 is a sectional view on the line 19—19 of Fig. 18.

Fig. 20 is a sectional view on the line 20—20 of Fig. 18.

Fig. 21 is a side elevation of the operating plunger.

5 Fig. 22 is a fragmentary elevation, showing in detail the locking dog for the rack gear.

10 Fig. 23 is a diagrammatic plan view, showing the different positions of throw of 10 the slide bars and swinging lever connected thereto.

Similar reference characters indicate corresponding parts throughout the several views in the drawings.

15 Referring to the drawings in detail, the vending apparatus comprises a casing or housing A, preferably made from metal, formed at its front with a pair of slide runways or guides 10 in which are arranged 20 coin slides 11, each being formed with a circular opening 12 which is of the size of the coin having a fixed valuation in the realm for receiving the same so that on the movement of the said slide 11 the coin will 25 be carried inwardly of the casing or housing A for the deposit thereof in a coin chute 14 which extends curvilinearly downwardly from a gage block 15 which receives the slide 11 from the runway or guide 10, and 30 has arranged therein a transversely disposed gage bridge 16 which determines the proper thickness of the coin placed within the opening 12 in the slide 11, and in event that the coin is of greater thickness than the gage 35 set by the gage bridge 16 the said slide will be prevented from moving inwardly for the deposit of such coin into the chute 14 internally of the casing or housing A of the machine. However, should the coin be of less 40 thickness than the set position of the gage bridge 16 it will be dropped into the chute 14 on moving the slide 11 inwardly when carrying the said coin, yet this particular coin will be ejected from the apparatus in a 45 manner presently described.

The slides 11 each is formed with a forwardly inclined loop handle 17 so that they can be readily moved by the operator of the apparatus. Journalized in the casing or housing A is a horizontal transversely disposed shaft 18 to which is fixed a rack gear 19 meshing with a vertically disposed rack bar 20 which has its lower end connected with certain operating mechanism, as for example a pump rod of a gasoline dispensing machine of any ordinary well-known construction so that on the upward movement of the rack bar 20 gasoline will be dispensed from the machine, the operation of the said 55 rack bar being controlled in a manner presently described.

Loosely journalized upon the shaft 18 is a driven gear 13 meshing with a driving pinion 21 fixed to an operating shaft 22 suitably 60 journalized in one side of the casing or hous-

ing A and also journalized in a brace bar 23 interiorly thereof, the said shaft 22 being projected without the housing or casing A and carries thereon a hand crank 24 so that it may be manually rotated. Formed on the driven gear 13 concentrically of the shaft 18 are a series of clutch pins 25, while splined or slidably keyed to the said shaft 18 is a clutch disk 26 having concentrically disposed apertures 27 therein for receiving the pins 25 to lock the gear 13 upon the said shaft 18, the clutch disk 26 being formed with an annularly grooved hub or collar 27' which is straddled by means of a fork or yoke 28 having its stem 29 swiveled in a link 30 provided with an elongated slot 31 in which works a pivot pin 32 mounted in an extension or arm 33 on a clutch operating lever 34, the link being formed with a socket 35 in which is received a coiled expansion spring 36 and a push bolt 37 which is acted upon by the said spring 36 for the positive engagement of the bolt 37 with the pivot 32, and in this manner the link is mounted for slight yielding movement so as to assure the positive clutch engagement of the clutch disk 26 with the clutch pins 25 on the gear 13 for the locking of the latter upon the shaft 18. The fork or yoke 28 carries a cross pin 38 which engages in the peripheral groove in the collar 27' for loosely connecting the clutch disk 26 with the fork or yoke 28 for the positive sliding movement of the clutch disk 26 on the movement of the clutch lever 34 which is actuated 100 in a manner presently described.

Connected to the lower end of the clutch lever 34 is a coiled retractile spring 39, the same being also connected to the casing or housing A so that the lever 34 will be held 105 under tension.

Arranged below the shaft 18 and within the housing or casing A are spaced parallel movable rails 40 and 41, respectively, each being formed at their forward ends with coin receivers 42 having pivoted therein coin releasing gates 43, each of said receivers and gates being provided with registering central openings 44, and acting upon each gate is a spring 45 which is carried by the receiver 42 so as to hold the gate 43 in position to retain the coin in the said receiver. The gate 43 is formed with a loop-like keeper 46 for the automatic tripping of the said gate in a manner presently described.

Fixed in and rising from the rails 40 and 41 at intermediate points thereof are abutment pins or lugs 47 with which engages a rod 48 mounted at right angles to and on the lower end of the clutch operating lever 34, and to this rod 48 is connected the spring 39 which tensions the said lever and thereby holds the rails 40 and 41 in normal rear-most position, and likewise holds the clutch lever 34 in a position so that the rod 48 130

will engage with the lugs 47 on the said sliding rails. Mounted on the front of the casing or housing A interiorly thereof at one side of the pair of sliding rails 40 and 41 is a sleeve 49 through which works a plunger 50 formed with a slotted outer end 51 in which works a pivot 52 on a hand operating lever 53 pivoted at 54 in a bearing 55 formed on the outer face of the front of the casing or housing A, and the free end of this lever 53 is provided with a handle 56 of any ordinary well-known construction.

Within the sleeve 49 which forms a guide for the plunger 50 is a coiled expansion spring 57, one end of which works against the front of the casing or housing A, while the other end works against a collar 58 fixed to the said plunger 50 so as to normally hold it inwardly of the casing or housing A, and fixed to this plunger 50 at right angles thereto intermediate its ends is an extension 59 from which projects forwardly thereof spaced parallel trip fingers 60, each having pivoted therein at their free ends gravity locking detents 61 which are adapted to automatically engage the keepers 46 on the coin gates 43 when coins are held within the receivers 42, and upon the outward pulling of the plunger 50 so that upon the release of the said plunger the gates 43 will be tripped to open position for the discharge of the coins from the receivers 42 and subsequently released by the trip detents 61 when the plunger 50 moves inwardly in the casing or housing A under the tension of the spring 57 acting thereon. Should there be no coin within the receiver 42 the fingers 60 on the extension 59 upon the plunger 50 when the latter moves outwardly of the casing or housing A will move through the registering openings 44 in the receivers 42 so that the rails 40 and 41 will not be advanced forwardly within the casing or housing A, which would be the result should the free ends of the fingers 60 abut coins held within the receivers 42 by the gates 43 when normally closed; and in this manner the said rails 40 and 41 are set for the operation of the apparatus in a manner presently described.

Formed at the inner end of the plunger 50 is a bifurcation 62 to which is pivotally connected a link 63 to which is connected a latch or locking pin 64 vertically slidably in a guide 65, the pin 64 being formed with an elongated slot 66 through which is passed the pivot 67 connecting it to the link 63, and carried within this pin 64, which is adapted to engage with any one of the teeth 60 of the gear 19 for locking the same on the advancement of the plunger 50, is a spring-held bolt or push pin 68 which acts upon the pivot 67 to normally hold the pin 64 extended, yet permitting the same to yield for the length of the slot 66 therein. When

the plunger 50 moves inwardly the locking pin 64 is disengaged from the gear 19 thereby freeing the same to permit rotation thereof, so that on the outward pull of the plunger the gear 19 cannot be rotated for the operation of the apparatus, it being understood of course that the slide rails 40 or 41 or both have been moved forwardly, which during such movement throws the clutch disk 26 into engagement with the clutch pins 25 for locking the driven gear 13 to the shaft 18 so that on operating the crank 24 the rack bar 20 can be operated after the plunger 50 has been moved inwardly of the casing or housing A, but the said rack bar 20 cannot be operated when the plunger 50 is being moved outwardly thereof.

Mounted on the rear wall of the casing or housing A at a point slightly elevated above the path of movement of the rails 40 and 41 are brackets 69 in which are pivoted locking dogs 70 for locking engagement with the rear ends of the said rails 40 and 41 after the same have been advanced so as to hold the said rails in such position, the said dogs being released in a manner presently described.

Located intermediate the movable rails 40 and 41 and fixed to the rear wall of the casing or housing A is a horizontally disposed guice bar 71 on which is slidably mounted a movable collar 72 having fixed therein an upstanding vertical latch pin 73 forming a pivot for a swinging lever 74 loosely connected thereto and having therein near opposite ends elongated slots 75 through which project pivot lugs 76 formed on and rising from the respective rails 40 and 41 so that the position of the latch pin 73 is changed when either of the said rails or both of the same are advanced forwardly for a purpose presently described.

Located between the shaft 18 and the plane of the movable rails 40 and 41 is a horizontally disposed rocking frame 77 having its side bars swingingly connected at their forward ends to a horizontal pivot 78 mounted in vertical uprights 79 stationarily supported within the casing or housing A, and in these side bars of the rocking frame 77 are formed guideways 80 in which is slidably fitted a keeper plate 81 having secured in its forward edge a pair of spaced parallel guide rods 82 which are mounted for sliding movement through the pivot 78 and have surrounding the same coiled expansion springs 83 which act upon the plate 81 to force the same rearwardly to the rear extremities of the guideways 80 in the side bars of the rocking frame 77 so as to be in a position to normally lie in the path of lifting hooks 84 which are pivoted to the locking dogs 70 and also pivoted to links 85 which are swingingly connected to pivot 130

ears or bearings 86 formed on the rear wall of the casing or housing A so that on the upward movement of the frame 77 when the keeper plate 81 is rearmost therein the hooks 84 will be lifted for releasing the dogs 70 from the movable rails 40 and 41, which under the action of the spring 39 will be shifted rearwardly to normal position, excepting in a manner hereinafter fully described.

Adjustably mounted on the rack bar 20 is a trip block 87 which is adapted to engage with the end in the path of movement thereof of a cross bar 88 mounted on the rear end 15 of the frame 77 so as to lift the latter on the upward movement of the rack bar 20 for the lifting of the hooks 84 and thereby disengage the locking dogs 70 from the movable rails 40 and 41 for freeing the same to move 20 rearwardly to normal position.

Fixed to the shaft 18 contiguous to the rack gear 19 is a ratchet gear 89 which has surrounding it a ratchet head 90 on the upper end of a substantially L-shaped rocking 25 arm 91, the same being swingingly connected to a stationary pivot 92 suitably mounted within the casing or housing A, and has its lower rearwardly disposed right angular branch portion 93 projected into the path 30 of a trip block 94 fixed on the rack bar 20 near the lower end thereof, the said right angular portion 93 at its extremity being fitted with a friction roller 95 which engages a beveled face 96 on the block 94 so that on 35 the lowering of the rack bar 20 the said block 94 will act upon the portion 93 of the arm 91 for rocking the same, and upon the pivot 92 for the latter are loosely connected ratchet pawls or dogs 97 which alternately 40 engage with the ratchet gear 89 for locking the shaft 18 against rotation in reverse directions, the pawls or dogs 91 being held in the head through the medium of guide straps 98 and work in a recess 99 formed in the 45 said head 90, and are limited in their approach toward and away from the ratchet gear 89 by the inner fasteners 100 connecting the straps 98 to the head and the walls of the recess 99, respectively. Connected to 50 the pawls or dogs 97 is a coiled retractile spring 101 which serves to hold the same against the fasteners 100 for the straps 98, and thereby sustain the same in working relation to the ratchet gear 89, it being seen 55 that on the rocking of the arm 91 one of the pawls or dogs 97 is engaged with the ratchet gear 89, thereby locking the shaft against rotation in one direction, and on the reverse swinging of the said arm 91 the other pawl 60 or dog 97 is engaged with the ratchet gear 89 for locking the shaft 18 against rotation in the reverse direction, the movement of the rack bar 20 being designed to control the ratchet arm 91 for the locking of the shaft 65 in a manner hereinbefore set forth.

The keeper plate 81 is formed in its under face with a row of spaced rearwardly tapering notches 102 in which engages the latch pin 73 to limit the sliding movement of the collar 72 on the bar 71 and thereby vary the 70 throw of the movable rails 40 and 41 for a purpose presently described.

Pivoted to the upper end of the upright 79 is a swinging locking arm 103 formed with a notch 104 in which is received a lip 75 or nib 105 formed on the ratchet head 90 so as to lock the same when the said lip or nib 105 is engaged with the arm 103 against swinging movement, the arm 91 of the ratchet head 90 being connected with a coiled 80 retractile spring 106 which is connected at the front of the casing or housing A to hold the said arm 91 under tension and thereby normally retain the lip or nib 105 engaged in the notch 102 in the locking arm 103, and 85 thus prevent rotation of the shaft 18 in one direction.

Fixed in the free end of the locking arm 103 is a depending releasing pin 107 which has its lower end engaged with the cross 90 bar 88 of the swinging frame 77 so that on the lifting of the said frame the arm 103 will be raised to release the ratchet head 90 so that the spring 106 connected with the arm 91 will become active to move it and 95 thereby shift the head 90 for permitting one of the ratchet dogs or pawls 97 to engage the ratchet gear 89 and thus lock the shaft 18 against reverse rotation while the rack bar 20 is moving downwardly, the said locking arm 103 being automatically released 100 from engagement with the ratchet wheel 89 on the upward movement of the said rack bar 20 by the engagement of the block 87 with the bar 88, the said block being carried 105 by the rack bar.

Mounted within the casing or housing A parallel with the brace bar 23 and directly over the keeper plate 81 is a cross strut 108 from which depends a lug 109 in which is 110 mounted a stop pin 110, the same being adapted to engage in any one of a series of spaced alining grooves or channels 111 when the frame 77 is elevated under the action of the block 87 on the rack bar 20 when moving 115 upwardly, and thereby limiting the movement of the keeper plate 81 in a step by step manner so as to control the quantity of gasoline to be delivered from the dispensing machine on the deposit of a coin or coins of 120 predetermined denominations in a manner presently described.

Located beneath the coin receivers 42 when the movable rails 40 and 41 are in normal position are coin receiving hoppers 112 125 which are carried by and form an entrance to coin return chutes 113, the same opening through the front wall of the casing or housing A and communicate with a receiving trough 114 without the latter, the said coin 130

receivers 42 being formed interiorly thereof with diametrically opposed gage noses 115 so that when a coin of a diameter less than the standard coin of a predetermined 5 nomination is received therein the said coin will pass the gage noses 115 and be discharged from the coin receivers into the hoppers 112 for the return of such coin through the chutes 113 to the trough 114, 10 and in this manner the said coins are ejected from the apparatus without possibility of the successful operation of the same.

It will also be apparent that by the particular arrangement of the gage noses 115, 15 should a thin coin be placed within the machine it will pass into the discharge hopper 112 for the return of the said coin through the chute 113 to the trough 114, and thus be ejected in this manner from the apparatus. 20 Mounted in the right angular ends of the movable rails 40 and 41 are adjustable screws 42' which serve to keep the gage noses 115 from approaching the inner wall of the coin receiver 42 nearer than the thickness 25 of the coin determined to be used or received in the coin receivers 42 so that if the coin is either too thin or of insufficient diameter it will be ejected, as it will pass these gage noses 115. These screws 42' also 30 make it possible to take up any wear, as will be clearly apparent.

It is of course understood that the swinging lever 74 can be pivoted at the correct place so that coins of different valuations 35 other than hereinbefore named when deposited within the apparatus will effect the operation thereof. Therefore, it is to be understood that by setting the apparatus in this manner coins of different denominations 40 can be used for the successful dispensing of the liquid therefrom. It is preferable that the apparatus be used for dispensing gasoline, although other liquids can be dispensed thereby, if desired.

45 Mounted on the inner face of the front wall of the casing or housing A is a coin box or depository 116 which is formed with inlet hoppers 117 for receiving the coins from the receivers 42 on the ends of the 50 movable rails 40 and 41 upon the opening of the gate 43 in the said receivers. Provided in the front wall of the casing or housing A for inspection of the inlet hoppers 117 are 55 peep openings 118 so that the coins can be visible therethrough, and such coins are stayed within the hoppers 117 through the medium of a tripping platform 119 formed on a tripping lever 120 swingingly supported upon a pivot 121 journaled in the depository 116, the said lever being extended upwardly through the top of the box or depository 116 and carries a spring-held trip 60 dog 122 which is adapted for engagement by the coin receivers 42 when being advanced 65 forwardly in the casing or housing A so that

the platform 119 will be tilted in the depository 116 to drop the previously deposited coin or coins therein. Now on the return or backward movement of either of the coin receivers 42 the dog 122 will be 70 tripped so as not to interfere with the return or backward movement of the said receivers 42 and the movable rails 40 and 41 carrying the same.

The depository or box 116 is provided at 75 one side with a door 123 so that access may be had thereto for removing the coins received therein, and access may be had to the casing or housing A through the removable or swinging section 124 at one side thereof. 80

Upon the movable rails 40 and 41 are supported coin shutters 125 which shut off the coin chutes 14 during the advancement of the coin receivers 42 on the said rails so as to prevent the choking of the apparatus 85 which would render the same inoperative, the said receivers 42 being in communication with the chutes 14 when in normal position so that the said chutes will be opened when such receivers are in normal position. 90

Surrounding the shaft 18 and fixed to one side of the casing or housing A is a spring barrel 126 in which is arranged a main spring 127, one end of which is fixed to the barrel and the opposite end thereof fixed to the shaft 18; and this spring is adapted to be wound on the upward movement of the rack bar 20 so that it will be automatically lowered when the rack gear 19 is released by the locking bolt 64 as hereinbefore set forth. 100

To advance either of the movable rails 40 and 41 it will be apparent that it is necessary for a coin to be held within the receiver 42 so that the fingers 60 will abut the said coins therein when the lever 53 is pulled outwardly for actuating the plunger 50 connected thereto, and when these rails 40 or 41 have been advanced forwardly the locking dogs 70 will engage the rear ends thereof and thus hold the same in their advanced 110 position, and during the advancement of either of the said rails 40 and 41 the clutch operating lever 34 is moved therewith for throwing the clutch disk 26 into engagement with the clutch pins 25, and thus the operating shaft 22 will be geared with the shaft 18 so that it is capable of rotation in one direction for elevating the rack bar 20 by the gear 19 thereon. 115

The clutch operating lever 34 is formed 120 with an extension 128 on which is mounted a lug 129 arranged in the path of the locking arm 103 so that when the clutch disk 26 is thrown into engagement with the clutch pins 25 the said locking arm 103 is 125 automatically lifted to free the ratchet head 90, and the spring 106 connected to the arm 91 thereof will move the said head to bring one of the dogs 97 therein into engagement with the ratchet gear 89 and thereby lock- 130

ing the shaft 18 against reverse rotation so that the rack bar 20 cannot be moved downwardly until arriving at its full upward stroke. Likewise the rack bar cannot be moved upwardly after reaching the limit of its lowermost stroke, because the ratchet arm 91 is acted upon by the block 94, which reverses the ratchet action and thereby locks the shaft 18 from rotation in a direction to elevate the rack bar 20 by the gear 19 meshing therewith.

The operation of the apparatus is as follows: Normally the rack bar 20 is in lowermost position and the block 94 has acted upon the roller 95 carried by the arm 91 so that the latter has been swung upon its pivot 92 and thus shifted the ratchet head 90 so that the dog 97 rearwardly of the ratchet gear 89 is engaged therewith, thereby locking the shaft 18 against rotation in one direction. The movable rails 40 and 41 are acted upon by the spring 39 so that the same will be pulled rearwardly of the casing, which is their normal position, and additionally this spring 39 acts upon the rod 48 so as to pull upon the clutch operating lever 34 to move the lower end thereof rearwardly 34 to move the lower end thereof rearwardly against the lugs 47 on the rails 40 and 41, and in this position the clutch disk 26 has been thrown out of engagement with the clutch pins 25 so that the gear 13 on the shaft 18 is free, and by reason thereof the hand crank 24 is out of driving transmission with the gear 13 so that upon the turning of the crank 24 the gear 21 will be rotated, and likewise the gear 13 will rotate, but the power transmission from the said crank 24 will not be imparted to the shaft 18, thus the said apparatus will remain inactive or passive. When the clutch operating lever 34 is moved rearwardly at its lower end the extension 128 with the lug 129 thereon is raised, lifting the locking arm 103 to release the lip or nib 105 on the ratchet head 90 so that the latter is free to be moved the instant the block 94 engages the roller 95 on the arm 91 so as to shift the ratchet mechanism and thereby locking the shaft 18 from reverse rotation.

When it is desired to deliver a predetermined quantity of gasoline from the dispensing machine, it being understood of course that by the deposit of a coin of a predetermined denomination in the receiver 42 on each movable rail 40 or 41 a predetermined quantity of gasoline will be dispensed from the machine, it will be assumed that the receiver 42 on the rail 40 is adapted to receive a coin having a twenty-five cents valuation, while the receiver 42 on the rail 41 is adapted to receive a coin having a fifty cents valuation, these coins being admitted to the said receivers from the chutes 14, and the coins are deposited therein from the coin slides 11 at the front of the casing or hous-

ing A of the apparatus. Now should two coins of the denominations above named be deposited in the receivers 42 a quantity of gasoline will be delivered from the dispensing machine equaling three times the quantity of gasoline that would be dispensed by the deposit of the coin of twenty-five cents valuation, while should a coin having the fifty cents valuation be deposited within the apparatus a quantity of gasoline would be dispensed from the machine equaling in quantity twice the quantity to be delivered by the deposit of a coin of twenty-five cents valuation.

Now, on the deposit of a coin of twenty-five cents valuation in the slide 11 communicating with the chute 14 leading to the coin receiver 42 on the movable rail 40 the apparatus can be operated, and this is accomplished by pulling outwardly upon the lever 53 which is connected with the plunger 50, the same being connected to the extension 59 which is mounted thereon, and this plunger moves forwardly simultaneously moving therewith the extension 59 carrying the parallel trip fingers 60, one of which engages the coin deposited within the receiver 42 which is held therein by the gate 43 so that as the plunger moves outwardly the movable rail 40 is advanced, while the other rail remains in normal position as the other finger 60 passes through the openings 44 in the other coin receiver 42 and its gate 43 as the said openings 44 are not obstructed by a coin in the said receiver. When the movable rail 40 advances the lug 47 thereon acts upon the rod 48 fastened to the clutch operating lever 34 causing it to swing in a direction to throw the clutch disk 26 into engagement with the clutch pins 25 on the gear 13, thereby locking the latter to the shaft 18 so that the hand crank 24 is in gear transmission with the said shaft 18 for rotating the same.

On the movement of the clutch operating lever 34 by the rail 40 the lug 129 on the extension 128 is lowered, thereby permitting the locking arm 103 to drop so that the lip or nib 105 will engage in the notch 104 in the said arm, thereby locking the ratchet head 90 against swinging movement so that one of the dogs 97 therein will engage the ratchet gear 89 so as to lock the shaft 18 against reverse movement during the lifting of the rack bar 20, and the rail 40 in its advanced position is automatically locked against rearward movement by the locking dog 70 pivoted to the rear wall of the casing or housing A. After the rail 40 has been advanced the hand lever 53 is released and the plunger 50 is acted upon by the spring 57 within the sleeve 49 so as to return the plunger to normal position within the casing or housing A, and during this movement of the plunger the extension 59 is moved rearwardly with the fingers 60, and

the latch 61 on the finger acting upon the coin in the receiver 42 on the rail 40 is engaged with the keeper 46 so that on the rearward movement of the said finger the gate 43 is tripped to open position, thereby releasing the coin from the receiver 42 for its deposit within the hopper 117 for its delivery into the depository 116, and the said rail 40 is sustained in its advanced position by the dog 70 engaging with the rear end thereof. On the advance movement of the lever 40 the swinging lever 74 pivoted to the collar 72 on the guide bar 71 has been shifted to an angular position, and during this movement the pin 73 acts upon the keeper plate 81 by reason of its engagement in one of the notches 102 in the under side thereof so as to advance the plate 81 a single notch out of the path of engagement with the lifting hooks 84 connected with the dog 70 for locking the movable rails 40 and 41, respectively. During the rotation of the shaft 18 the gear 19 is similarly moved for lifting the rack bar 20, which during its upward movement is connected with the gasoline dispensing machine for dispensing the gasoline therefrom, and when this rack bar 20 reaches a predetermined height the block 87 engages the cross bar 88 so as to lift the frame 77 and the keeper plate 81 therein, which latter is automatically released from the latch pin 73, and under the action of the springs 83 working against the same is caused to move rearwardly for engagement with the lifting hooks 84 so that on further upward movement of the rack bar 20 the said hooks 84 are raised and the locking dog 70 is disengaged from the rear end of the movable rail 40, thereby freeing the same so that it will move rearwardly to normal position under the action of the spring 39, and simultaneously therewith the clutch operating lever 34 will be acted upon by the said spring so as to swing the same in a direction to throw the clutch disk 26 out of engagement with the clutch pins 25, thus freeing the gear 13 on the shaft 18 so that further rotation of the shaft cannot be had by operating the crank 24 on the operating shaft 22 and thus stopping the apparatus so that no further gasoline can be dispensed from the machine until another coin is deposited in the apparatus.

When the frame 77 is lifted by the block 87 the locking arm 103 is lifted out of engagement with the nib 105 on the ratchet head 90 so that the arm 91 under the action of the spring 106 will move the ratchet head 90 to throw one of the dogs 97 out of engagement with the ratchet gear 89 and the other dog 97 into engagement with the ratchet gear so as to lock the shaft 18 from further rotation in a direction to continue the operation of the apparatus for the further dispensing of gasoline from the dispensing machine. The main spring 127 in the barrel 126 is wound on the upward movement of the rack bar 20, and after the clutch disk 26 has been thrown out of engagement with the clutch pins 25 the said spring will become active to lower the rack bar 20 to normal position, and when it reaches its normal position the block 94 will act upon the arm 91 to reverse the ratchet mechanism so that the rack can be again raised when the clutch is thrown in on the deposit of another coin in the apparatus.

Now, should it be desired to dispense twice the quantity of gasoline from the machine than that dispensed on the deposit of a coin having a twenty-five cents valuation, it is necessary to deposit within the machine a coin having a fifty cents valuation, and the operation of the machine is repeated as hereinbefore set forth, with the exception that the rail 41 is moved in contradistinction to movement of the rail 40, it being apparent that when the plunger 50 moves forwardly the link 63 is moved in a vertical position so as to force the latch pin 64 into engagement with the gear 19, thereby locking the same against rotation in either direction, so that it will be impossible to operate the apparatus until the plunger 50 has moved inwardly or returned to normal position. On the movement of the rail 41 the lever 74 is thrown to a reverse angular position, thereby moving the pin 73 twice the distance of movement thereof when actuated by the lever 40 so that the keeper plate 81 has been shifted the distance of two of the notches 102 in the under side thereof. When the rack bar 20 has moved upwardly a predetermined distance the frame 77 is tilted, so that the pin 73 is released from one notch for the escapement of the keeper plate 81 which moves the distance of a single notch by reason of the pin 110 engaging in the second groove or channel 111 in the series in the upper side of the plate 81 when the frame 77 is lifted, and as the latter moves upwardly the arm 102 releases the ratchet head so that the ratchet mechanism is reversed, thereby locking the ratchet gear 89 against further turning movement for the lifting of the rack bar 20 so that under the action of the spring 127 in the barrel 126 the latter is returned to lowered position, and on the instant it reaches its lowermost point of movement the ratchet mechanism is again reversed, thereby permitting the bar to be again lifted until the block 87 trips the frame 77 to release the pin 73 from engagement in the second notch 102 in the under side thereof, and at this instant the plate 81 is moved to its rearmost position for engagement with the lifting hooks 84 so that on further upward movement of the rack bar 20 the dog 70 is released from the rail

41 to permit the latter to return to normal rearmost position, whereupon the apparatus is locked against further operation and the rack bar 20 is again returned to normal lowered position therein.

5 Upon the deposit of two coins of twenty-five cents and fifty cents valuation both rails 40 and 41 are advanced so that the pin 73 is moved by the lever 74 a distance three 10 times the distance of movement of the said pin by the advance of the rail 40 on the deposit of a coin of twenty-five cents valuation, so that three times the quantity of gasoline is dispensed from the machine on the 15 deposit of the two coins therein of the valuation named. When these two coins are deposited it is necessary for the rack bar 20 to be raised three times, and this is provided for by the escapement of the keeper plate 20 81 as it is alternately engaged by the pins 73 and 110, respectively, at opposite sides thereof before it is moved into a position to engage the lifting hooks 84 which release the dogs 70 so that the rails 40 and 41 can be returned rearwardly to normal position.

25 From the foregoing description, taken in connection with the accompanying drawings, the construction and manner of operation of the device will be clearly understood, and therefore a more extended explanation has been omitted.

What is claimed is:—

1. An apparatus of the class described comprising a casing having coin chutes 35 therein, means for delivering coins of predetermined denominations into said chutes, movable members having coin receivers, means for locking the movable members in position for the reception of coins in the 40 receivers, means for moving either or both of the members only on the deposit of coins in the receivers, and mechanism operative on actuating the movable members.

2. An apparatus of the class described 45 comprising a casing having coin chutes therein, means for delivering coins of predetermined denominations into said chutes, movable members having coin receivers, means for locking the movable members in position for the reception of coins in the receivers, means for moving either or both 50 of the members only on the deposit of coins in the receivers, mechanism operative on actuating the movable members, means for locking the said members and means operated by the said mechanism for releasing the said locking means.

3. An apparatus of the class described 60 comprising a plurality of movable members arranged for operation under predetermined conditions, means for locking the movable members in advanced position, a movable rack, a gear for operating the rack, means for driving the gear, clutch mechanism controlled by the movement of the members

either singly or collectively for connecting and disconnecting the driving means for the rack gear, and means operated upon by the rack to release the locking means for the members.

4. An apparatus of the class described comprising a plurality of movable members arranged for operation under predetermined conditions, means for locking the movable members in advanced position, a movable 75 rack, a gear for operating the rack, means for driving the gear, clutch mechanism controlled by the movement of the members either singly or collectively for connecting and disconnecting the driving means for the 80 rack gear, means operated upon by the rack to release the locking means for the members, and means for returning the members to normal position and automatically releasing the clutch mechanism.

5. An apparatus of the class described comprising a plurality of movable members arranged for operation under predetermined conditions, means for locking the movable members in advanced position, a movable 85 rack, a gear for operating the rack, means for driving the gear, clutch mechanism controlled by the movement of the members either singly or collectively for connecting and disconnecting the driving means for the 90 rack gear, means operated upon by the rack to release the locking means for the members, and means for returning the members to normal position and automatically releasing the clutch mechanism and reversing ratchet 95 mechanism controlling the direction of rotation of the rack gear and actuated by the rack.

6. An apparatus of the class described comprising a plurality of movable members arranged for operation under predetermined 100 conditions, means for locking the movable members in advanced position, a movable rack, a gear for operating the rack, means for driving the gear, clutch mechanism controlled by the movement of the members either singly or collectively for connecting and disconnecting the driving means for the 105 rack gear, means operated upon by the rack to release the locking means for the members, means for returning the members to normal position and automatically releasing the clutch mechanism, reversing ratchet mechanism controlling the direction of rotation of the rack gear, and actuated 110 by the rack, and means for locking the gear against rotation when actuating either or both of the members.

7. An apparatus of the class described comprising a plurality of movable members arranged for operation under predetermined 115 conditions, means for locking the movable members in advanced position, a movable rack, a gear for operating the rack, means for driving the gear, clutch mechanism controlled by the movement of the members either singly or collectively for connecting and disconnecting the driving means for the 120 rack gear, means operated upon by the rack to release the locking means for the members, means for returning the members to normal position and automatically releasing the clutch mechanism, reversing ratchet mechanism controlling the direction of rotation of the rack gear, and actuated 125 by the rack, and means for locking the gear against rotation when actuating either or both of the members.

trolled by the movement of the members either singly or collectively for connecting and disconnecting the driving means for the rack gear, means operated upon by the rack to 5 release the locking means for the members, means for returning the members to normal position and automatically releasing the clutch mechanism, reversing ratchet mechanism controlling the direction of rotation 10 of the rack gear and actuated by the rack, means for locking the gear against rotation when actuating either or both of the members, an escapement for controlling the locking means and means for automatically adjusting the escapement on movement of the 15 said members.

8. An apparatus of the class described comprising a plurality of movable members arranged for operation under predetermined 20 conditions, means for locking the movable members in advanced position, a movable rack, a gear for operating the rack, means for driving the gear, clutch mechanism controlled by the movement of the members 25 either singly or collectively for connecting and disconnecting the driving means for the rack gear, means operated upon by the rack to release the locking means for the members, means for returning the members 30 to normal position and automatically releasing the clutch mechanism, reversing ratchet mechanism controlling the direction of rotation of the rack gear and actuated by the rack, means for locking the gear against 35 rotation when actuating either or both of the members, an escapement for controlling the locking means, means for automatically adjusting the escapement on movement of 40 said members, and an adjustable trip means on the rack and constituting the means for actuating the means for releasing the locking means for the members.

9. An apparatus of the class described comprising a plurality of movable members arranged for operation under predetermined 45 conditions, means for locking the movable members in advanced position, a movable rack, a gear for operating the rack, means for driving the gear, clutch mechanism controlled by the movement of the members 50 either singly or collectively for connecting and disconnecting the driving means for the rack gear, means operated upon by the rack to release the locking means for the members, means for returning the members to

normal position and automatically releasing the clutch mechanism, reversing ratchet mechanism controlling the direction of rotation of the rack gear and actuated by the rack, means for locking the gear against rotation when actuating either or both of the members, an escapement for controlling the locking means, means for automatically adjusting the escapement on movement of the 60 said members, an adjustable trip means on the rack and constituting the means for actuating the means for releasing the locking means for the members, and means for locking the reversing ratchet mechanism and automatically actuated on the movement of 65 the rack.

10. An apparatus of the class described comprising a plurality of movable members arranged for operation under predetermined 70 conditions, means for locking the movable members in advanced position, a movable rack, a gear for operating the rack, means for driving the gear, clutch mechanism controlled by the movement of the members either singly or collectively for connecting 75 and disconnecting the driving means for the rack gear, means operated upon by the rack to release the locking means for the members, means for returning the members to normal position and automatically releasing 80 the clutch mechanism, reversing ratchet mechanism controlling the direction of rotation of the rack gear and actuated by the rack, means for locking the gear against rotation when actuating either or both of the 85 members, an escapement for controlling the locking means, means for automatically adjusting the escapement on movement of said members, an adjustable trip means on the 90 rack and constituting the means for actuating the means for releasing the locking means for the members, means for locking the reversing ratchet mechanism and automatically actuated on the movement of the rack, and means on the clutch operated means for 95 permitting the ratchet locking means to engage the ratchet mechanism when the clutch mechanism is thrown in.

In testimony whereof I affix my signature in presence of two witnesses.
